UNITED STATES PATENT OFFICE.

CHARLES A. BERKEY, OF HIGHLAND PARK, MICHIGAN.

DESIGN FOR A SOCIETY-EMBLEM.

49,532.

Specification for Design.

Patented Aug. 22, 1916.

Application filed June 28, 1916. Serial No. 106,531. Term of patent 7 years.

To all whom it may concern:

Be it known that I, CHARLES A. BERKEY, a citizen of the United States, residing at Highland Park, in the county of Wayne and State of Michigan, have invented a new, original, and ornamental Design for a Society-Emblem, of which the following is a specification, reference being had to the accompanying drawing, forming part thereof.

The figure is a plan view of a society emblem illustrating my new design.

I claim:

The ornamental design for a society emblem as shown.

CHAS. A. BERKEY.
